UNITED STATES PATENT OFFICE.

LEWIS E. ARNOLD, OF HONOLULU, TERRITORY OF HAWAII.

VACUUM-BOX FOR FRUIT-CANNING.

1,216,260.

Specification of Letters Patent. Patented Feb. 20, 1917.

Application filed August 5, 1914. Serial No. 855,318.

To all whom it may concern:

Be it known that I, LEWIS E. ARNOLD, a citizen of the United States, residing at Honolulu, county of Honolulu, Territory of Hawaii, have invented certain new and useful Improvements in Vacuum-Boxes for Fruit-Canning; and I do hereby declare the following to be a full, clear, and exact description of the invention, such as will 10 enable others skilled in the art to which it appertains to make and use the same.

This invention relates to fruit canning, and particularly to means for subjecting the open top filled cans to a vacuum; and the 15 object of the invention is to produce a simple and efficient apparatus for this purpose.

The invention contemplates, a long rectangular shaped box, a door for each end, 20 a plurality of rollers arranged transversely along the bottom of this box, and on which trays bearing a number of the filled open top cans may be rolled into and out of the box, a pipe provided with a valve connecting the interior of this box with a suitable air exhausting device, and means for breaking the vacuum, as will hereinafter more 25 fully appear.

The invention consists in the novel construction and combination of parts, reference being had to the accompanying drawings, forming a part of this specification, in which—

Figure 1 represents in side elevation a 35 preferred form of apparatus embodying my present invention. Fig. 2 is a section on the line A—A of Fig. 1.

Referring to the drawings, 5 is the long 40 rectangular shaped box preferably of cast iron. Each of the doors 6, for closing the ends of the box 5, are hingeably mounted between the outer ends of the arms 7 and 8 on opposite sides of the box 5 respectively. The arms 7 are pivoted on the pins 9 in 45 the sides of the box 5. The arms 8 are pivoted on the pins 10 in the lugs 5^a on the top of the box 5. Each of the arms 8 is extended at 8^a and provided with a weight 11 to counterweight the doors 6. Each door 50 6 may thus be swung upward to provide access to the interior of the box 5. A gasket 12 may be interposed between the end of

the box 5 and a door 6 to seal the joint when the door is closed.

A plurality of rollers 13, each provided 55 with trunnions 14 adapted to turn in the notches 15 in the two rectangular bars 16, are arranged transversely within the box 5, as shown.

The pipe 17, provided with the valve 18, 60 connects the interior of the box 5 with a suitable air exhausting device. The valve 19, connected by the nipple 20 to the box 5, may be used for breaking the vacuum within the box 5.

In operation, a door 6 is raised, a tray 21 bearing thereon a number of filled open top cans 22 is pushed into the box 5, and then other trays successively until the box 5 is filled, the trays moving easily upon the rollers 13. One tray 21 is shown in the drawings having thereon a dozen cans 22 although more or less cans may of course be thus handled. When the box 5 has been filled as described, the door 6 is then lowered 75 until closed, the valve 19 being closed the valve 18 is now opened. The box 5 is thus evacuated to withdraw the air and gases from the fruit in the cans as well as the air from within the box 5. The valve 18 80 is then closed, and the vacuum is broken by opening the valve 19. Both doors 6 are now swung upward and the trays bearing the treated cans are pushed forward and rolled outward upon the rollers 13 and discharged from the box 5 by the insertion of 85 a new set of trays bearing other cans which are to be similarly treated.

I claim:

1. A vacuum-box for fruit canning comprising, a long rectangular shaped box, a door for each end, a plurality of rollers arranged transversely and removably over the bottom of the box and upon which trays bearing open top filled cans may be rolled 95 into and out of said box, means for producing a vacuum within the box, and means for breaking this vacuum, substantially as described.

2. A vacuum-box for fruit canning comprising, a long rectangular shaped box, a door for each end hingeably supported between the outer ends of arms pivoted to the box, two bars provided with notches and

placed longitudinally within the box, rollers adapted to turn in said notches, and means for producing and for breaking a vacuum within the box, substantially as described.

3. A vacuum-box for fruit canning comprising, a long rectangular shaped box, a door for each end hinged between the outer ends of arms pivoted to the box, two bars 10 provided with notches, rollers adapted to

turn trunnioned in said notches, means for producing and for breaking a vacuum within the box, and means for counterweighting said doors, substantially as described.

In testimony whereof I affix my signature, 15 in presence of two witnesses.

LEWIS E. ARNOLD.
